UNITED STATES PATENT OFFICE.

JOHN C. LACKNER, OF NEW YORK, N. Y.

DESIGN FOR A PAPER CASE FOR CONFECTIONERS' USE.

SPECIFICATION forming part of Design No. 12,414, dated August 16, 1881.

Application filed June 25, 1881. Term of patent 7 years.

To all whom it may concern:

Be it known that I, JOHN C. LACKNER, of the city, county, and State of New York, have invented a new and original Design for Paper Cases for Confectioners' Use, of which the following is a specification, reference being had to the accompanying drawing, forming part thereof.

Heretofore cylindrical or square paper cases, 10 without any ornamentation whatever, have been used by confectioners for holding fine cakes, creams, jellies, charlotte-russes, and like confectionery.

In the accompanying drawing, Figure 1 is a 15 perspective view of my newly-designed paper case for confectioners' use.

The paper casing A has an elliptical or like form, and a prow, B, at one end, so that it resembles a boat or ship. The upper edge is 20 decorated with tucks or scallops C, and this imitation boat may rest on a base made to represent water.

The imitation boat may be provided with a mast, E, and sail F, or some other marine emblem.

The several parts may be colored differently.

As the boat is open on top the charlotte-russe or other cake can be placed into it very conveniently.

Having thus fully described my invention, I 30 claim as new and desire to secure by Design Patent—

1. The design for paper cases for confectioners' use, the same consisting in an imitation ship or boat, of elliptical form, having a prow 35 at one end and a scalloped upper edge.

2. The design for paper cases for confectioners' use, the same consisting of the elliptical-shaped case A, provided with a prow, B, so as to resemble a boat.

3. The design for paper cases for confectioners' use, the same consisting of an elliptical-shaped case, A, provided with a prow, B, and a tucked scalloped edge, C.

JOHN C. LACKNER.
